UNITED STATES PATENT OFFICE.

LEWIS W. MALLASEE AND FRANK B. NIMICK, OF PITTSBURG, PA.

CRANE FOR CRUCIBLE-FURNACES.

SPECIFICATION forming part of Letters Patent No. 310,695, dated January 13, 1885.

Application filed January 14, 1884. (No model.)

To all whom it may concern:

Be it known that we, LEWIS W. MALLASEE and FRANK B. NIMICK, both of Pittsburgh, in the county of Allegheny and State 5 of Pennsylvania, have invented a new and useful Improvement in Cranes for Crucible-Furnaces; and we do hereby declare the following to be a full, clear, and exact description thereof, reference being had to the accompanying drawings, forming a part of this specification, in which—

Figure 1 is a view of our improved crucible-furnace appliances. Fig. 2 is a view of the pouring-shank or teeming-tongs, and Fig. 15 3 is a detail.

Like letters of reference indicate like parts wherever they occur.

Heretofore it has been customary to use small crucibles, capable of holding a charge 20 of about one hundred pounds, for melting steel in crucible-furnaces, for the reason that such crucibles are raised out of the furnace by hand, which is an arduous and difficult operation, requiring considerable skill on the 25 part of the workman. For making large ingots and castings the use of these small crucibles is objectionable, because the contents of several crucibles are necessary to obtain the requisite amount of metal for the purpose, 30 and the character of the steel in different crucibles is frequently not uniform, and hence the castings are not always homogeneous. Furthermore, a large number of such crucibles are required, and charging them is necessarily 35 a very frequent operation and requires as much time and nearly the same amount of labor as would be needed in charging an equal number of much larger crucibles. In pouring or teeming the metal one man handled 40 each crucible singly, and although they are relatively much smaller than the ones we use, yet the labor of teeming, owing to the position of the teemer's body, which the weight of the metal and the care and precision with 45 which it has to be poured into the molds to prevent cutting them render it necessary for him to assume, makes the operation extremely severe and exhausting. The small size of the crucibles requires a considerable number of 50 teemers, which increases the cost of the steel, as it involves skilled labor. All these objec-

tions are overcome by the use of our invention, which enables us to use crucibles of at least double the size of the old ones, and yet handle them with much greater ease and with 55 a lower grade of and consequently cheaper labor and fewer workmen. It also enables us to produce a more uniform grade of steel, and consequently better castings.

To enable others skilled in the art to make 60 and use our invention, we will now describe it by reference to the drawings.

Here *a* represents an ordinary gas crucible-furnace; *b*, the bottom, and *c* a crucible.

Arranged at the side of the furnace *a* is a 65 crane, *d*, preferably hydraulic, having a swinging jib, *d'*, on which is a runner or carrier, *e*, having suspension hook or ring *e'*. The crane is so arranged relatively to the furnace that its jib swings over and commands the mouth 70 of the latter, so that a suitable pair of tongs, *g*, suspended by chain *g* to the carrier *e*, can be lowered into and raised out of the furnace thereby, for the purpose of inserting and removing the crucibles. These crucibles are 75 very much larger than those heretofore used, and their use is rendered possible by the employment and arrangement of the crane *d*, not only from the fact that it has the necessary strength to handle them, but also because it 80 raises and lowers them by a direct vertical movement, and not by the somewhat lateral swing or jerk by which the workmen heretofore raised the crucible out of the furnace, and which had a tendency to strain and injure it and pull it apart, with the loss of the charge. It also enables the crucible to be placed on the floor without shock or jar, while heretofore it frequently happened otherwise, owing to the weight and momentum as well 85 90 as to the want of skill and lack of sufficient strength on the part of the workman, to the detriment and often destruction of the crucible, loss of the steel, and danger to the workman from the escaping molten steel. The tongs *g* have curved gripping-jaws *g'*, which encircle 95 the crucible, and arms or handles *g''*, which are locked together by a rack-bar or segment, *h*, pivoted to one of them and extending through a slot in the other, where it is held in 100 place by a spring, *g''*. In teeming, a two-handled tool, *k*, called a "teeming-shank,"

having a lever end, *k*, and a straight handle, *k'*, is used. The latter is held and supported by an ordinary laborer, while the teemer holds the lever end and tips the crucible thereby to pour the charge into the mold. In this operation a common laborer is substituted for a teemer in pouring an equal quantity of metal, because by the old method each crucible is poured by a teemer, and in pouring the same amount of metal two or more such crucibles would need to be used, which, in making a large casting, would have to be poured at the same time.

The work of charging involves weighing the stock to obtain proper uniformity of weight and proportions. It is just as easy to weigh a large charge as a small one, while the frequency of charging is lessened, owing to the size of the crucible.

What we claim as our invention, and desire to secure by Letters Patent, is—

A crucible-handling appliance consisting of a swinging jib extending horizontally above the crucible-furnace, and adapted to be elevated and lowered in a vertical direction above the same, of a traveling carrier adapted to be moved along the jib, and provided with a hook for the suspension of the crucible-tongs, whereby the crucible may be elevated in a strictly vertical position without tendency to tilting or shaking by the positive upward movement of the jib, substantially as specified.

In testimony whereof we have hereunto set our hands this 28th day of December, A. D. 1883.

LEWIS W. MALLASEE.
FRANK B. NIMICK.
